UNITED STATES PATENT OFFICE.

EUGENE PATZNER, OF FOUNTAIN CITY, WISCONSIN.

SWIVEL-HINGE-GATE OPENER AND CLOSER.

1,269,114.

Specification of Letters Patent. Patented June 11, 1918.

Application filed February 12, 1917. Serial No. 148,160.

To all whom it may concern:

Be it known that I, EUGENE PATZNER, a citizen of the United States of America, residing at Fountain City, in the county of 5 Buffalo and State of Wisconsin, have invented certain new and useful Improvements in Swivel-Hinge-Gate Openers and Closers, of which the following is a specification, reference being had therein to the 10 accompanying drawing.

This invention relates to a gate and has for its principal object the production of a swivel hinge gate opener and closer.

Another object of this invention is the 15 production of a gate wherein a bar and lever are secured and carried so that when in their normal positions, they will retain the gate in a closed position, although when moved toward a closed position, they will pull the 20 gate to an open position.

Another object of this invention is the production of a gate opener and closer wherein a pivotally mounted rod is employed for supporting one end of the lever, 25 thereby permitting the necessary swinging movement of the rear end of the lever as the gate is being moved to an open or closed position.

A still further object of this invention is 30 the production of a gate opener and closer wherein a standard is provided with a frame formed therein, whereby the standard may support one end of the lever and also carry the cables so as to permit the cables to be 35 extended to a desired position.

With these and other objects in view, this 40 invention consists of certain novel constructions, combinations and arrangements of parts as will be hereinafter more fully described and claimed:

In the accompanying drawings:

Figure 1 is a side elevation of the gate 45 opener and closer as constructed in accordance with this invention.

Fig. 2 is a top plan view of the gate 50 opener and closer showing the portions of the cables taken away and illustrating the cables and supports moved slightly from their correct positions.

Fig. 3 is a front elevation of the gate 55 opener and closer.

Fig. 4 is an enlarged fragmentary sectional view through a portion of the device,

illustrating the manner in which the cables are carried by the cable supports. 55

Fig. 5 is a fragmentary bottom plan view of the inner end of the bar and the lever showing the same detached.

Fig. 6 is a longitudinal sectional view 60 through the structure shown in Fig. 5.

Fig. 7 is a fragmentary detail perspective view of the standard and frame.

Fig. 8 is a section taken on the line 8-8 of Fig. 2.

Fig. 9 is a bottom plan view of the forward end of the bar.

Fig. 10 is a longitudinal sectional view through the structure shown in Fig. 9.

Referring to the accompanying drawings by numerals, it will be seen that the gate 70 opener and closer is adapted to be used in combination with a fence comprising the usual fence posts 1 to which the strands 2 are secured in any suitable manner, while the gate 3 is pivotally mounted upon one of 75 the posts 1 by means of the usual hinges 4. This construction of a gate is the usual manner in which the same is mounted and therefore, it is obvious that the gate opener and closer is adapted to be used in connection with any ordinary pivotally mounted 80 gate.

The standard 5 is positioned at a distance from one of the posts 1 and to one side thereof as shown clearly in Figs. 1, 2 and 3, 85 although this standard 5 is comparatively short. The frame 6 is formed integral upon the standard 5 as indicated at 7, and this frame 6 extends to one side of the standard 5 as shown clearly in Figs. 1 and 7. This 90 frame 6 is elongated and terminates in the overhanging end 8 which extends across the upper end of the standard 5, although at a spaced distance therefrom. The purpose of this overhanging end will be specifically disclosed hereinafter. 95

The U-shaped bracket 9 is secured by means of the bolts or screws 10 to the standard 5 adjacent its upper end as shown clearly in Fig. 7. This bracket 9 has registering openings 11 through which the vertical portion 12 of the inverted L-shaped rod 13 extends as shown in Fig. 8. By having the vertical portion of this rod 12 extending through the openings 11, it will be 100 seen that the rod will be free to pivot upon 105

the bracket although the horizontal extension 14 and this rod will bear upon the upper end of the bracket as shown in Fig. 8 and thus limit the downward movement of 5 the rod.

The lever 15 is elongated and has a strip 16 carried in an adjusted position thereon by means of the retaining bolts 16. It will be noted by referring particularly to Fig. 5, 10 that the strip 16 is provided with a plurality of longitudinally extending slots 18 through which the bolts 17 extend, thereby allowing the strips 16 to be held in an adjusted set position upon the lever 15 as above 15 designated. This strip 16 is rolled at one end to provide the sleeve 19, which fits upon the horizontal position 14 of the inverted L-shaped rod 13. A hinge 20 is fixedly mounted by means of the screws 21 upon the opposite end of the lever 15 and this hinge 20 is also secured by screws 21' to the inner end of the bar 22. This bar 22 is also elongated and is much longer than the lever 15 as shown clearly in Fig. 2 and has an elongated plate 23 riveted or secured by any 25 other suitable securing means as shown at 24 at its outer end. This plate 23 has a ring 25 formed integral upon its outer end and it should be understood that this ring 25 will 30 be carried at a distance beyond the outer end of the bar 22. A bracket 26 has its feet 27 secured by rivets or bolts 28 to the gate 3 and this bracket 26 passes through the ring 25 of the plate 23 for supporting the 35 forward end of the bar 22.

An eye 29 is carried by the inner end of the bar 22 as shown in Fig. 6 and to this eye 29 the inner ends of the cables 30 are secured as indicated at 31. These cables 30 extend 40 upwardly through the eyes 32 which are secured to the overhanging end 8 of the frame 6 as shown in Figs. 1 to 3 inclusive. These cables 30 then extend at substantially right angles to the eyes 32 carried by the overhanging end 8 of the frame 6 so as to pass 45 over the pulleys 33 carried by the bracket and bolt as indicated at 34 to one end of the cross bar 35 mounted upon each post 36. These cross bars 35 are braced as indicated 50 at 37 so as to be held in their correct positions. The cables 30 then depend downwardly as shown at 38 so as to have a grip loop 39. It will be further seen that these cables 30 are at all times retained in a taut 55 position by means of the weights 40.

When this gate opener and closer is in use, it will normally assume the position as shown in Figs. 1 to 3 inclusive. At this time, it will be seen that the bar and lever 60 will be extending in alinement with each other and as a consequence, it will be impossible to open the gate by merely pushing thereagainst owing to the dead center condition of the bar and lever. When, however, it is desired to open the gate, this ac-

tion may be easily accomplished, even from a vehicle if necessary, by the operator gripping the loop 39 and pulling downwardly thereon. By pulling one of the loops, it will be seen that one of the cables 30 will be drawn through one of the eyes 32 and over one of the pulleys 33, thereby pulling upwardly upon the eye 31 carried by the bar 22. While this action is taking place, it is obvious that the weight 40 upon the remaining cable will take up the slack in the cable and cause the cable to remain in a taut condition as above set forth. By the pulling upon one of the cables 30 and the lifting of the eye 29, it will be seen that the inner end of the bar 22 will be swung upwardly as will the forward end of the lever 15. This action is permitted because of the pivotal connection of the bar lever. While this action is taking place, it will be seen that by drawing upwardly upon the inner end of the bar 22, the forward end of the bar will be drawn toward the standard 5 and as a consequence will pull upon the bracket 26 and thus swing the gate toward an open position. While this action is taking place, it is obvious that the position of the pivot point with respect to the standard and the bracket 26 will be changed and, therefore, the inverted L-shaped rod 13 will be swung 95 upon the bracket 9, thus allowing the inner end of the lever 15 to be swung to accommodate the action necessary for the movement of the lever at its forward end and the bar at its inner end upwardly. Continued pulling upon the cable will, of course, bring the gate to an open position of various degrees. As soon as the cable is released, it will be seen that the weight of the bar and lever will cause the gate to be swung to a closed position and the bar and lever to assume their normal positions as shown in Figs. 1 to 3 inclusive. If, however, it is desired to swing the gate to a full open position, the cable which has just been pulled should be 105 given an extra jerk so as to cause the lever 15 to move across a dead center after which the lever will swing downwardly away from the gate 3 while the bar 22 will move downwardly until resting upon the lower surface 110 of the lever 15, which has just been swung over to extend in the opposite direction from the position normally assumed. This action will of course move the gate to an open position at a full extent and then either of the cables is again pulled downwardly at the loop 39 so as to swing the lever 15 upwardly to pass over a dead center at which time, the weight of the bar and lever will cause the gate to be moved to a closed position. 115

From the foregoing description, it will be seen that a very efficient gate opener and closer is provided wherein the bar and lever are pivotally supported so as to permit action thereon due to pulling upon either 120

- one of the two cables to move the gate to an open position or move the gate to a closed position when the cable is released, while the mounting of the inner end of the lever 5 upon the pivotally mounted L-shaped rod will permit the necessary action of one end of the lever and bar as the gate is being moved to an open position or closed position.
- 10 It will be further seen that a very efficient and simple standard and frame have been provided which are formed as indicated to permit a bracket to be carried upon which the inverted L-shaped rod is supported while 15 the frame is formed upon the standard so as to extend for a considerable distance thereabove for carrying eyes through which the operating cables extend. Furthermore by having this frame extending to one side 20 of the standard, it will be seen that the upper end of the standard is unobstructed thereby allowing sufficient space for the free movement of the rod to the inner end of the lever.
- 25 It is obvious that after the gate has been started by the upward movement of the rear end of the bar and the forward end of the lever, the momentum acquired by the gate will cause the lever to move across the 30 dead center when the gate is being moved to an open position. When the gate is being moved to a closed position, the momentum acquired by the gate in the opposite direction will also swing the lever across a dead 35 center, after which the weight of the bar and lever in combination with the momen-
- tum of the gate will cause the gate to be entirely closed.
- What is claimed is:
1. In a device of the class described, the 40 combination of a hingedly supported gate, a post, a bracket carried upon said post, said bracket having alined openings formed therein, a sectional bar pivotally connected to said gate, said bar having a sleeve carried 45 upon its rear end and an inverted L-shaped rod having an inner end portion projecting through the openings of said bracket, whereby said rod will be supported, said rod also projecting through said sleeve for piv- 50 otally and retainably supporting the rear end of said sectional bar, and means for moving said bar.
  2. In a device of the class described, the 55 combination of a hingedly supported gate, a standard, a frame formed integral upon said standard, said frame being off-set with respect to one side of said standard, said frame terminating in an overhanging portion, a bracket carried upon said frame, a 60 rod pivotally supported upon said bracket, a sectional bar pivotally secured to said gate and carried by said rod, pulleys connected to the overhanging portion of said frame, cables passing around said pulleys and con- 65 nected to said bar, whereby said bar may move so as to swing said gate, and the off-set frame permitting the swinging move- ment of said bar, without interference.
- In testimony whereof I hereunto affix 70 my signature.

EUGENE PATZNER.
